UNITED STATES PATENT OFFICE.

BENJAMIN MARSH, OF ALBANY, NEW YORK, ASSIGNOR TO MARSH & HOFFMAN, OF SAME PLACE.

DESIGN FOR A SPOON.

SPECIFICATION forming part of Design No. 20,948, dated July 21, 1891.

Application filed March 25, 1891. Serial No. 386,414. Term of patent 3½ years.

To all whom it may concern:

Be it known that I, BENJAMIN MARSH, a citizen of the United States, residing at Albany, in the county of Albany and State of New York, have invented certain new and useful Improvements in Designs for Spoons; and I do hereby declare the following to be a full, clear, and exact description of the invention, such as will enable others skilled in the art to which it appertains to make and use the same.

The accompanying cut-print illustrates my design for spoons.

On the outer end portion of the handle A of the spoon is the figure a of a man attired in

the dress of a "Knickerbocker" of the seventeenth century and seated on a chair and facing the beholder and smoking a pipe. On the lower end portion of handle A is the figure b of a sturgeon, with its tail at the bowl B. 20

What I claim is—

The design for a spoon herein described and shown, the same consisting of the figure a of a man attired in the dress of a Knickerbocker, seated on a chair, and the figure b of a sturgeon, as set forth.

BENJAMIN MARSH.
